FUEL DISTRIBUTION AND VAPORIZATION

Filed Dec. 14, 1921

UNITED STATES PATENT OFFICE

HOMER A. TRUSSELL, OF CHICAGO, ILLINOIS

FUEL DISTRIBUTION AND VAPORIZATION

Application filed December 14, 1921. Serial No. 522,419.

My invention relates to improvements in fuel distribution and vaporization, primarily for internal combustion engines, and has among its various objects the provision of a construction which,

First, automatically regulates the proportion of fuel vapor and air to produce the most economical mixture throughout the entire range of engine operation;

10 Second, maintains the manifold pressure used for idling as a proximate minimum, thereby obviating unnecessary fuel and lubricating oil consumption when the engine is running at high speed with the throttle 15 closed or in idling position;

Third, increases the proportion of air admitted to the working fluid with any degree of throttle opening when the engine speed approaches, equals or exceeds the maximum 20 that would be produced by the fuel volume being admitted;

Fourth, prevents liquid fuel from entering the combustion chamber;

25 Fifth, isolates liquid fuel from the general intake passage, vaporizes this fuel and mixes it with air, this mixture being admitted to the general intake passage and in turn to the combustion chamber;

Sixth, facilitates starting by admitting air 30 to the working fluid, this is especially effective in case the starting choker is kept closed too long or in case the choker is used when the engine is warm;

35 Seventh, furnishes an efficient and convenient method of priming to accomplish starting a cold engine supplied with heavy fuel;

Eighth, accomplishes thorough vaporization 40 of the fuel with the minimum application of heat to the working fluid.

I attain these objects by the mechanism illustrated in the accompanying drawings, in which—

45 Figure 1 is a side elevation of an engine fitted with a manifold and regulator constructed according to the invention;

Figure 2 is an end view of the manifold;

50 Figure 3 is a partially broken vertical section of the manifold and showing the regulator in place;

Figure 4 is an enlarged section taken on line 4—4 of Fig. 3 coupled with a section of the engine valve port;

Figure 5 is an enlarged central section of the regulator; and

Figure 6 is a modification of the device shown in Figures 3 and 4.

In the particular structure illustrated in the drawings, the invention is applied to an integral inlet and exhaust manifold the precise arrangement, however, need not be adhered to as the structure is susceptible of various changes and modifications which may be made without departing from the spirit of the invention.

The invention is shown applied to a two cylinder internal combustion engine, it being understood, however, that it is not limited to this particular type of engine, and it is obvious that the invention is applicable to internal combustion engines employing any number of cylinders.

The manifold 10, includes the inlet passage 11, the exhaust passage 12, the pocket 13, and the by-passes 14 14. This manifold provides communication from the carburetor 15, through the inlet passage 11, to the cylinders 16 16, and from these cylinders through the exhaust passage 12, to the atmosphere.

The pocket 13, the by-passes 14 14, and portions of the inlet passage 11, adjacent these by-passes are separated from the exhaust passage 12, by a thin wall and consequently become heated very quickly by exhaust gases; the uppermost orifices of the by-passes 14 14, (Fig. 4) are situated in the lowest parts of the inlet passage 11, and these by-passes open into the pocket 13, at their lower end; the heat is applied to the lower sides of the by-passes 14 14, and the pocket 13.

The regulator 17, includes the priming cup and air inlet 18, the fluid passage 19, the valve 20, which is interposed between the inlet 18, and the passage 19, the manually controlled spring 21, the adjustable spring container 22, the throttle controlled spring 23, which opposes the action of the spring 21, the loosely journalled spring container 24, the bell crank 25, the fluid heating tube 26, and the electrical heating coil 27, one end 27a of the coil

27, is connected to the cup 28, which is grounded, the other end 27b of the coil 27, is connected to the tube 26, the insulation 28, holds the tube 26, and the coil 27, in place and 5 prevents short circuiting.

The spring 29, and the insulated terminal 30, (Fig. 4) provide the electrical connection to the tube 26. This electrical heater is intended for starting use only and can be connected to be operated in conjunction with the starting choker or independently, this is immaterial just so the current is applied to the coil 27, when difficulty in starting is encountered due to low temperature or heavy fuels, 10 the pocket 13, and the by-passes 14 14, being heated by the exhaust gases in the passage 12, when the engine is running under its own power.

The regulator 17, is mounted in the manifold 10, so as to deliver fluid through the passage 19, into the lower part of the pocket 13, and subsequently through the by-passes 14 14, and the inlet passage 11, to the cylinders 16 16.

25. The bell crank 25, is to be operated by the throttle control mechanism so that when the throttle is opened the spring container 24, will be moved toward the center of the regulator 17, thereby compressing the spring 23, 30 which will oppose the pressure applied to the valve 20, by the spring 21, but the maximum tension of the spring 23, will never be sufficient to force the valve 20, off its seat without the aid of atmospheric pressure and intake suction; thus the passage of air from the inlet 18, past the valve 20, and to the passage 19, becomes less restricted with an increase of throttle opening, this is desirable because higher manifold pressure is encountered with increased throttle opening and consequently less spring pressure is needed to control the valve 20.

The carburetor 15, is a conventional type fitted with a starting choker and a throttle 45 valve; adjusted for power and flexibility.

In starting the engine, fluid will be admitted past the valve 20, if the choker is closed but not until the inlet manifold pressure is sufficiently low to draw an adequate supply 50 of fuel from the carburetor: If the fuel being used in the carburetor 15, is not volatile enough to be used for starting, a priming charge of more volatile fuel can be put in the inlet 18, this priming charge will not pass the valve 20, until the manifold pressure is sufficiently 55 low to insure high velocity of the priming charge and air through the passage 19, and the by-passes 14 14, this high velocity expedites vaporization and admixture of the priming charge and the air.

The first part of the priming charge admitted to the passage 19, will consist of liquid fuel if the inlet 18, has been provided with enough fuel to submerge the valve 20, the 65 proportion of fuel to air will gradually de-

crease as the fuel level in the inlet 18, becomes lower until air only is admitted.

Any unvaporized portion of the priming charge and of the fuel coming from the carburetor will gravitate into the pocket 13, and become vaporized by the ebullition created by the hot air ejected from the submerged outlet of the tube 26, through the liquid fuel. This fuel in the pocket becomes heavier as the engine continues to run, due to the vaporization of the more volatile fuels and the accumulation of fuel from the carburetor. But the pocket 13, and the by-passes 14 14, are getting hotter with each succeeding impulse which promotes the process of vaporization; the choker is to be released as rapidly as the engine shows indication of overrichness of the working fluid.

The regulator facilitates starting by withholding the priming charge until the intake suction is sufficiently high to rapidly carry it to the combustion chambers, resulting in the instantaneous liberation of sufficient fuel into the inlet passage to prime all of the cylinders; the rapid decrease of fuel and increase of air admitted by the regulator prevents the engine from quickly stalling due to an over-rich mixture if the starting choker is kept closed too long.

Manipulation of the starting choker is made less troublesome than with the conventional carbureting system which instantly floods the cylinders with an over-rich charge and stops the engine unless the choker is partially opened as soon as the working fluid is rich enough to burn.

When the engine is running idle and throttled down to the minimum speed at which it will be required to run, the tension of the spring 21, should be adjusted by means of the threaded spring container 22, so that the valve 20, will admit the maximum amount of air with which the engine will continue to idle properly; engine will fire irregularly or stop if too much air is admitted to the working fluid, due to insufficient tension of the spring 21.

When an engine is rotated at high speed with the throttle valve closed or in idling position, as is the case with an automobile coasting with the engine being used as a brake, high intake suction will be created which tends to draw more lubricating oil past the pistons into the combustion chamber and to draw more fuel past the throttle valve; this will be obviated by the regulator which will admit air into the inlet in volume increasing with increased engine speed, thereby precluding this high intake suction and this waste of lubricating oil and fuel, and the engine will be more responsive to the throttle because of the elimination of the surplus oil which would accumulate and smolder in the combustion chamber aggravated by the fluid drawn from the exhaust pas-

sage; this pumping of fluid to and from the combustion chamber and the exhaust passage is also mitigated by the admission of the additional air.

5 Little or no air is admitted through the regulator whenever the engine is loaded enough to hold it below approximately half the maximum speed that the engine could attain from the fuel received through a given 10 throttle opening; as soon as the engine exceeds this speed the pressure in the inlet passage is decreased and consequently more air is admitted by the regulator in volume increasing with increasing engine speed until 15 the working fluid is lean enough that additional air tends to retard the engine speed, a decrease in engine speed unaccompanied by a change in throttle opening permits an increase of pressure in the inlet manifold which 20 causes a reduction in the amount of air admitted to the working fluid by the regulator, thus the leanest mixture that can be used to advantage is automatically obtained due to the variable pressure of the valve 20, toward 25 its seat accomplished by the relative tension of the springs 21, and 23, and to the differential pressures at the inlet 18, and the passage 19, encountered at different speeds with various throttle openings.

30 Any fuel remaining in liquid form after encountering the hottest portion of the inlet passage 11, will drain into the by-passes 14 14, and gravitate in contact with the hottest portion of these toward the pocket 13, the 35 heat of these by-passes and the air admitted to them by the regulator 17, serves to vaporize the fuel and return it to the manifold 11, liquid fuel which may accumulate in the pocket 13, is volatilized by the heat of this 40 pocket and the air admitted to the bottom of the pocket 13, by the regulator 17.

Liquid fuel is kept in the inlet passage 11, as long as is safe, in view of the probability of its being drawn into the combustion chamber, so that vaporization of the liquid fuel will be accomplished, in so far as possible, by the heat of the passage 11, any liquid fuel which may reach the pocket 13, from the carburetor 15, while the engine is at normal 45 working temperature will have traveled through the passage 11, and the by-passes 14 14, encountering increasing temperatures enroute which has served to vaporize fuels of various degrees of volatility as rapidly as 50 sufficiently high temperatures were encountered, the portion which has reached the pocket consists of the fuel heavy ends and if not separated from the working fluid could 55 not be vaporized by heat without heating the working fluid sufficiently to materially reduce volumetric efficiency. Thus vaporization of the liquid fuel contained in the working fluid will be accomplished with the minimum 60 application of heat and without heating 65

the entire working fluid sufficiently to vaporize the fuel heavy ends.

The modification shown in Fig. 6 is similar in construction to that disclosed in Figures 3 and 4 differing in that the lowest point in the inlet passage is beyond the manifold 10, the circumferential groove 32, is provided in the valve port 31, to break the liquid film adhering to the wall of this valve port and to collect liquid fuel, and the by-pass extension 33, is provided in the cylinder 16, the upper end of this extension terminates in this groove and the lower end connects with the by-pass 14.

This structure is desirable when the valve port 31, can be modified to conform to this arrangement in that the by-pass 33, is situated to deliver a priming charge at high velocity adjacent the entrance to the combustion chamber; liquid fuel in the working fluid comes in contact with greater area and consequently absorbs more heat before entering the by-pass 14, thereby vaporizing more of the liquid without removing it from the working fluid passages 11, and 31; liquid fuel in the valve port 31, and the adjacent portion of the passage 11, drains toward the groove 32 and the by-pass extension 33, in the same direction that the working fluid is moving; air admitted by the regulator 17, is delivered through the passages 14, and 33, to the working fluid in the valve port 31, adjacent the entrance to the combustion chamber, which promotes stratification of the inflammable fluid and air in the combustion chamber thereby permitting the use of a greater amount of air.

Having thus described the invention, what I claim and desire to cover by Letters Patent is:

1. An internal combustion engine priming device provided with a heating element; a receptacle for a priming charge; a passage communicating with a working fluid inlet; said element being situated in said passage, and means permitting the transfer of fluid from said receptacle to said passage, said means preventing this transfer of fluid to said passage and the contact of said fluid with said element unless the suction in said passage is sufficiently high to cause rapid travel of said fluid therein.

2. In a fuel induction system the combination of a primary fuel inlet passage, a pocket below the same, a fluid passage connecting said inlet passage with said pocket, a vapor passage connecting said pocket and inlet passage with a combustion chamber and downwardly extending means for admitting air directly into said pocket at a point below the top of said pocket and adjacent but spaced from the bottom thereof.

3. In a fuel induction system, the combination of a direct fuel inlet passage, a pocket, a fluid passage connecting said inlet passage with said pocket, a vapor passage connecting

said pocket and inlet passage with a combustion chamber and means adapted to admit fluid directly into said pocket, said means comprising a passage, means for heating said passage and a valve for regulating flow of fuel into said passage.

4. In a fuel induction system, the combination of a direct fuel inlet passage, a pocket adapted to receive fluid from said inlet passage, means for converting said fluid into vapor and returning said vapor to said inlet passage and means for admitting heated fluid directly into said pocket, said means comprising a passage having a fuel flow regulator therein, and means for heating said passage.

5. In combination, a direct fuel inlet passage, a pocket, a fluid passage connecting said inlet passage with said pocket, an exhaust passage adapted to heat said pocket, a vapor passage connecting said inlet passage and pocket with combustion chambers, and means for admitting fluid directly into said pocket, said means comprising a passage, a valve regulating said passage and means to heat fluid passing from said passage into the pocket.

6. In a fuel induction system, a fuel passage leading to an engine combustion chamber, a pocket remote from said passage and adapted to receive liquid fuel from it through a fluid passage connecting said fuel passage with said pocket, means for heating said pocket with exhaust gas, a vapor passage connecting said pocket with said combustion chamber and means for admitting fluid into said pocket independently of said fuel passage and in direct proportion to the speed of said engine during normal running of said engine.

40 7. In a fuel induction system, a carburetor, a primary fuel mixture passage leading from said carburetor to an engine combustion chamber, a pocket below said passage, a restricted passage connecting said fuel mixture passage and said pocket, means for heating said pocket, a passage for delivering vapor from said pocket to said combustion chamber, and means independent of said carburetor for admitting a progressively leaner mixture of fuel and air directly into said pocket.

8. In combination with an internal combustion engine, a carburetor, a fuel passage connecting said carburetor with a combustion chamber of said engine, a sump below and separate from said passage inlet arranged to receive liquid fuel from said passage, and means for converting said liquid fuel into an explosive mixture in said sump and then returning it to said passage, said last mentioned means including automatic means for delivering auxiliary air to said sump in varying quantities during normal running of said engine.

9. In a fuel induction system for an internal combustion engine, a carburetor, a fuel

mixture passage connecting said carburetor with a combustion chamber of said engine, a sump below and separate from said passage inlet arranged to receive liquid fuel from said passage, means for converting said liquid fuel into an explosive mixture in said sump and then returning it to said passage and automatic means for delivering auxiliary air to said main passage through said sump during normal running of said engine.

10. In a fuel induction system, a sump below the main induction passage and separate therefrom arranged to receive liquid fuel from said passage and means for carbureting auxiliary air with said liquid fuel in said sump and delivering this carbureted air to said passage, said means including means for automatically delivering said air to said sump in varying quantity so that it will become carbureted to explosive form.

11. In a fuel induction system for an internal combustion engine, a trap to receive unvaporized fuel from the charge in ingress and means for converting said unvaporized fuel into combustible form and then returning it to said charge, said means including means operative during normal running of said engine for automatically supplying auxiliary air in varying amounts to compensate for the amount of said unvaporized fuel being converted and to maintain the correct air-fuel ratio to produce said combustible form.

12. In a fuel induction system for an internal combustion engine, a pocket connected with the induction passage adapted to receive liquid fuel present in said passage between the throttle valve and the engine, and an air passage leading from above the fuel level of said pocket to substantially the bottom of said pocket for increasing the air supply to said passage and spraying the fuel collected in said pocket.

13. In a fuel induction system for an internal combustion engine, a primary induction passage, a sump below and separate from said passage arranged to receive liquid fuel therefrom, means for heating said sump dependent upon running of said engine, and other means for heating said sump independent of the running of said engine.

14. In a fuel induction system for an internal combustion engine, a primary induction passage, a sump below said passage, means for draining liquid fuel from said passage into said sump, a passage leading from a point adjacent the bottom of said sump to a point above said sump and opening into the air, and valvular means in the last mentioned passage comprising a valve adapted to close said passage, spring means constantly urging said valve to closed position, spring means urging said valve toward open position, and means for controlling the tension of the last mentioned spring means.

15. In a fuel induction system for an internal combustion engine, a primary induction passage, a sump below said passage, means for draining liquid fuel from said passage into said sump, a passage leading from a point adjacent the bottom of said sump to a point above said sump and opening into the air, and valvular means in the last mentioned passage comprising a valve adapted to close said passage, spring means constantly urging said valve to closed position, spring means urging said valve toward open position, and means for controlling the tension of the last mentioned spring means in direct relation to the throttling of said engine whereby the first mentioned spring means is rendered less effective at greater engine speeds. 5
16. In a fuel induction system for an internal combustion engine, in combination, an intake manifold, an exhaust manifold, a sump below said intake manifold, means for draining unvaporized fuel particles from said intake manifold into said sump, a common wall between said sump and said exhaust manifold whereby said liquid fuel in said sump will be heated, a passageway leading from the air above said sump terminating close to the bottom of said sump, valvular means in said passageway for admitting air 20 to said sump in direct relation to the speed of said engine, and means for returning the fuel vaporized in said sump mixed with air from said passage to said intake manifold. 25
17. In a fuel induction system for an internal combustion engine, in combination, an intake manifold, an exhaust manifold, a sump below said intake manifold, means for draining unvaporized fuel particles from said intake manifold into said sump, a common wall between said sump and said exhaust manifold whereby said liquid fuel in said sump will be heated, a passageway leading from the air above said sump terminating close to the bottom of said sump, said 30 passageway being formed for the direct reception of liquid fuel and including a tube surrounded by an electrical heating element, valvular means in said passageway, means for controlling said valvular means in direct 35 relation to the speed of said engine, and means for passing a mixture of fuel and air from said sump to said intake manifold. 40
18. In a fuel induction system for an internal combustion engine, a fuel mixture passage leading to a combustion chamber of said engine, a throttled carburetor connected to the intake end of said fuel mixture passage, a sump remote from said passage and adapted to receive liquid fuel accumulating in said 45 fuel mixture passage, a passage connecting said fuel mixture passage with said sump for conducting said liquid fuel from said fuel mixture passage to said sump, and means whereby air may be admitted directly into 50 said sump during normal operation of said 55
- engine whereby to change said liquid fuel particles in said sump to a combustible mixture which may flow to said combustion chamber through said passages. 60
19. In a fuel induction system, a fuel mixture passage leading to an engine combustion chamber, a pocket, a passage connecting said fuel mixture passage with said pocket, a passage for admitting air directly into said pocket, means for regulating the flow of air through the last mentioned passage in direct proportion to the speed of said engine, and means for heating said air enroute to said pocket. 70
20. In a fuel induction system for an internal combustion engine, a fuel mixture passage leading to a combustion chamber of said engine, a pocket adapted to receive liquid fuel from said fuel mixture passage, means for converting said liquid fuel into vapor in said pocket and delivering said vapor to said fuel mixture passage, and means for admitting heated air into said pocket in amounts directly proportional to the speed of said engine. 80
21. In a fuel induction system for an internal combustion engine, a carburetor, a fuel mixture passage connecting said carburetor with a combustion chamber of said engine, a pocket adapted to receive liquid fuel from said fuel mixture passage, means for supplying auxiliary air directly into said pocket, and means for heating said fuel and air in said pocket. 85
22. In a fuel induction system for an internal combustion engine, a carburetor, a fuel mixture passage leading from said carburetor to a combustion chamber of said engine, a sump adapted to receive liquid fuel from said passage, means for vaporizing said liquid fuel in said sump including the introduction of auxiliary air into said sump during normal continued operation of said engine, and means for delivering the mixture of the vaporized liquid fuel and auxiliary air to said combustion chamber. 90
23. In a fuel induction system for an internal combustion engine, a carburetor, a fuel mixture passage leading from said carburetor to a combustion chamber of said engine, a pocket separate from said passage, means for drawing liquid fuel from said passage into said pocket and returning said liquid fuel in vaporized form to said passage, said means including means independent of said carburetor for introducing auxiliary air and the application of heat to said drained fuel in said pocket for vaporizing said drained fuel and preparing it into a combustible mixture before redelivery to said passage, the volume of said auxiliary air being automatically regulated to maintain a predetermined fuel to air ratio. 100
